JOHN C. BEACH AND HENRY W. BEACH, OF SAN FRANCISCO, CALIFORNIA.

DISAPPEARING BED.

1,110,526.

Patented Sept. 15, 1914.

Application filed December 22, 1913. Serial No. 808,133.

To all whom it may concern:

Be it known that we, JOHN C. BEACH and HENRY W. BEACH, citizens of the United States, residing in the city and county of San Francisco and State of California, have invented new and useful Improvements in Disappearing Beds, of which the following is a specification.

This invention relates to wall beds.

The present invention has for its object to provide a disappearing bed, the mattress-bearing structure of which is in two articulated sections, each bearing a portion or section of the mattress and closable in a closet structure which may be formed in the wall or be independent thereof; the recess being of considerably less height than the full length of the mattress, thus providing an economical structure or wall receptacle for the contiguous section of the bed, when folded for non-use. This object is attained by providing a tiltable portion of a bed-frame with a portion of mattress, and connecting to said portion another section of the bed-frame which is movable horizontally, and automatically operates the coacting section of the frame.

It is a further object of the present invention to provide a wall or disappearing bed structure free of any door structure, and which, while occupying a minimum vertical and transverse space in the wall, will have a portion projecting in front of the wall usable as a desk, table, dresser, or other article of furniture.

Another object is to provide a bed structure, involving a horizontally movable carrier and bed-frame section suitably ornamented and finished as an article of furniture, movable toward and from a recess in the closet, and having operating connections, with a complementary section of the bed-frame which is pivoted in the wall recess so as to be swung to a vertical or horizontal position with relation to the wall, and to provide a readily adjustable counterbalancing means for a tiltable bed section.

Another object is to provide, in combination with a closet having a recess of suitable transverse depth and vertical height, a bed-frame member tiltable from the recess outwardly to a horizontal position; to provide a horizontally movable bed-frame portion connected to and operating the tiltable portion; and to provide an automatically operating closure or shutter which may consist

of an ornamental article or piece of furniture for covering a portion of the wall recess, means being provided for latching the horizontally movable bed section and carrier to the wall structure and for latching the automatically movable closure to the horizontally movable part.

The invention consists in combination with a closet structure having a suitable recess, a bed-frame of two sections, one of which is tiltable in the recess and the other of which is horizontally movable, each carrying a section of mattress, and the sections being articulated for coaction with means for locking the several parts in their respective positions, and having counterbalancing means for aiding in the operation of the tiltable bed section.

It also comprises details of construction which will be more fully explained by reference to the accompanying drawings, in which—

Figure 1 is a front view of the bed structure in partial vertical section. Fig. 2 is a transverse vertical section of the bed structure. Fig. 3 is a horizontal section on the line x—x of Fig. 2. Fig. 4 is a detail view of the tensioning device of the counterbalancing frame. Fig. 5 is a sectional view of the extended bed.

In its illustrated embodiment, there is shown a portion of a wall 2, through the lower portion of which there extends a closet structure or recess 3, which may be internally paneled, if desired.

It is one of the objects of the present invention to provide a wall bed which has a bed-frame of, preferably, two sections, the shorter of which, as 4, is supported upon and in a suitably finished horizontally movable cabinet or carrier structure 5, provided with rollers 6 running upon the floor 7. The longer section 8 of the bed-frame is turnably supported by the sectional shaft 9 in suitable foot-bearings 10, of which there is one on each side of the bed-frame section 8, which may be rigidly secured to a transverse base board 11, mounted upon the floor 7 within the closet or recess 3. The bed-frame sections 4 and 8 are provided respectively with mattress sections 12 and 13.

In order to automatically move the bed-frame section 8 from a vertical to a horizontal position, as the cabinet structure 5 is moved outwardly, these bed-frame members are connected by links 14, the inner

ends of which are turnably connected to pivots 15. The outer ends of the links 14 are connected to the short section 4, slidably mounted on rails 16 of the cabinet 5. Thus, when the cabinet 5 is moved outwardly from the wall, the bed links 14 pull upon the pivots 15 and in turn tilt the section 8 downwardly and outwardly about the bearings 10, so that the sections 4 and 8 10 register horizontally and form a complete bed with a mattress 12—13 of full length.

The cabinet 5 is locked, when in juxtaposition to the wall, in front of the recess 3, by a suitable latching device 18, having 15 hooks 19 at the inner end adapted to fit over respective keepers 20 fastened to the pilasters or finished panels at the sides of the recess 3. In order to disengage the hooks 19 from their respective stop plates 20 there 20 may be provided an operating lever 21, pivotally mounted on the front of the cabinet 5 and which has a short arm 22 projecting into the interior of the cabinet and engaging the adjacent end of the latch 18 which is 25 pivoted at 23.

While it is understood that the horizontally movable structure 5 of the bed may be of any height and desired finish, as here shown it is finished in the form of a buffet 30 and extends upwardly to a convenient height. Since the bed-frame section 8 is of greater length than the height of the cabinet 5, and, since it is, therefore, necessary to provide clearance room beneath the 35 top of the recess 3 for the frame section 8 to swing outwardly, it is desirable that this clearance way be concealed by a suitable means when the cabinet structure 5 is not of itself of sufficient height. To that end, there 40 is provided in this instance a frame 24, which may include a mirror, parallelly movable behind fixed pilasters 25, one on each side of the recess 3. The closure 24, when in its lowermost position, is engaged and retained by a snap latch 26 of the cabinet structure 5, which latch operates to hold the frame 24 down against the lifting tendency of counterweights 27, connected by ropes 28 to the frame, the ropes running over suitable pulleys 29 and the weights operating 50 in weight boxes 30 provided therefor. To guide the closure when it projects above the guides 25 the frame has legs 24' running in the guideways.

55 In operation, when it is desired to adjust the bed in horizontal usable position, the attendant or operator simply grasps the operating handle 21 and pulling upon the same unlatches the hooks 19 from their keepers 60 20, thus clearing the cabinet 5 and permitting its free horizontal movement over the floor upon the rollers 6. As the cabinet moves outwardly from the front of the recess 3 the latch 26 clears the closure or 65 frame 24, in front of the recess, and this

automatically rises a sufficient height to permit the tiltable section 8 to swing outwardly as the cabinet 5 is rolled away from the wall.

For the purpose of automatically checking the rising closure or mirror 24, as it approaches its upward limit of movement, there is mounted in front stiles 31 of the weight boxes 30 springs 32 which react upon wedge or brake blocks 33, attached to the 70 rear surface of the side members of the mirror frame 24; the friction of the brake spring 32 upon the tapering brake blocks 33 effectually and gradually bringing the closure to a stop in its upper position. To 75 positively prevent excessive upward movement of the mirror frame 24 there may be fastened thereon cushion stops 34 engageable with fixed cushion stops or bumpers 35 appropriately mounted with relation to 80 each other so that the bumpers 35 will engage the stops 34 and positively prevent the mirror frame 24 from entirely leaving its guideways behind the pilasters 25.

The mirror or closure 24 is pulled downwardly into closing position in front of the recess 3 when the cabinet 5 has been pushed toward the wall to raise the tiltable frame 8 into concealed position. The mirror is then latched in its lowermost position by the 90 device 26. When the bed-frame sections 4—8 are moved into horizontal position an automatically operating head-board 36, which is pivoted at 37 on brackets or arms 38 of the inner end of the section 8, will 95 automatically move into a vertical position at the inner or head end of the bed when the latter is horizontal. The automatic action of the head-board 36 is obtained by counterbalancing the same by the provision 100 of suitable weights 39 secured to the head-board 36, below the pivots 37, so that the head part is automatically maintained in 105 vertical position during the tilting action of the bed-frame 8 about its bearing journals 110.

From the foregoing it will be seen that an operator, when adjusting the bed from one position to the other, simply pulls upon the handle 21, which is fastened to the cabinet 115 5, and this latter moves horizontally toward or from the wall 2. As the entire load of the cabinet 5 is supported upon the rollers 6 very little exertion is required to move the cabinet 5.

In order to render the upward tilting operation of the bed-frame section 8 easy and semi-automatic, there is attached to each end of the shaft 9 a substantial counterbalancing spring 40, here shown as a spiral spring, 125 the inner end of which is splined in the contiguous portion of the shaft 9, and the longer or outer end of which reacts against the under surface of the adjacent rail of the bed-frame 8 and tends to tilt the latter 130

upwardly about the journals 10. Owing to the possible difference of strength of the springs 40, and for the purpose of equalizing their turning pressure against the rails of the bed-frame 8, the shaft 9 is preferably made in two sections with the contiguous ends supported in a sleeve 41. Upon each of the sections of the shaft 9 there is splined a clutch member 42, Fig. 4, the toothed surface of which engages a complementary toothed surface 43 of the respective journal brackets. Reacting to throw the clutch members 42 against the fixed toothed surface 43 are springs 44, supported at their outer ends by suitable clamp collars 45 on the sections of shaft 9. By these devices when the leaf springs 40 are adjusted upon the respective ends of the shaft 9, then by simply turning the respective clutch collar 42, this being splined upon the shaft section 9 will turn the latter and wind or unwind the spring 40, as the case may be, so as to increase or decrease the reaction upon the contiguous rail of the bed section 8. The force of each of the springs can be nicely adjusted or equalized so that the turning moment of the springs, against the sides of the bed section 8, will be substantially uniform.

The function of the springs 40 is to automatically tilt the bed section 8 upwardly as the carrier or cabinet structure 5 is moved toward the wall. In the reverse operation, or when the bed is to be adjusted horizontally while the cabinet 5 is being moved away from the wall, the necessary coaction between the bed-frame section 4 and the section 8 is had through means of the operating links 14, which are turnably connected to the section 4 on the truck cabinet 5 and to the pivots 15 to draw the bed part 8 down. An additional advantage of the present wall bed is that ample ventilation is provided when the bed is in the concealed position by the free circulation of air inwardly beneath the cabinet 5, and thence upwardly through the recess or closet 3 and out at apertures or crevices formed in the structure adjacent to the top of the closet.

From the foregoing it will be seen that we have provided a wall bed which does not require the operator or attendant to lift a heavy bed-frame or to turn a heavy door or bed-carrying structure about a pivot. The entire operation of the present bed is accomplished by simply pulling upon the handle 21 of the cabinet 5, which latter rolls easily across the floor, substantially the only resistance encountered to the folding operation of the bed structure being that of the counterbalancing springs 40.

Now since the present bed-frame is divided into sections 4 and 8 it will be seen that the weight of the tiltable bed-frame, as, for instance, the section 8, is a great deal less than the weight of a full length integral

bed-frame with all of the bedding, and, therefore, we are able to use counterbalancing devices, such as the springs 40, of much less strength than where a full length bed-frame is involved.

An important feature of this bed is that by connecting the tiltable bed section to the sliding part the upward momentum of the swinging frame is checked by the resistance of the rolling part. It is not necessary by our construction to recess the wall, since the closure may be erected in front and along one side of the wall.

When the bed is erected horizontally, the sliding part 4 projects from the carriage cabinet 5 so that the full length of the bed part is usable.

Having thus described our invention what we claim and desire to secure by Letters Patent is—

1. A disappearing bed comprising the combination of a relatively fixed closet structure and a movable cabinet structure or truck forming a movable front thereof, each having a section of the bed-frame and each section carrying a section of mattress, and means connecting the truck and the bed-frame section in the closet whereby said bed-frame sections may be moved into horizontal alinement for use.

2. The combination with a recess or closet structure, of a section of a bed-frame foldably mounted in the recess, and a complementary section of bed-frame horizontally movable toward and from the recess to form, when the bed sections are in horizontal alinement, a complete, full-length bed structure.

3. The combination with a closet structure, of a section of a bed-frame foldably mounted in the structure, a complementary section of bed-frame horizontally movable toward and from the closet structure to form, when the bed sections are in horizontal alinement, a complete, full-length bed structure, and means connecting the horizontally movable bed section and the tiltable bed section whereby they automatically coöperate to move into horizontal alinement and to right angular position for non-use.

4. The combination with a closet structure, of a section of a bed-frame foldably mounted in the structure, a complementary section of bed-frame horizontally movable toward and from the closet structure to form, when the bed sections are in horizontal alinement, a complete, full-length bed structure, means connecting the horizontally movable bed section and the tiltable bed section whereby they automatically coöperate to move into horizontal alinement and to right angular position for non-use, and a counterbalancing means for upwardly operating the tiltable bed-frame.

5. The combination with a recess or closet, of a bed-frame divided into a plurality of

sections, one of which is tiltably mounted in the recess and the other of which is horizontally movable toward and from said recess, and means connecting said bed-frame sections whereby they automatically coöperate to form a bed-frame of full length when in a horizontal position.

6. The combination with a recess or closet, of a bed-frame divided into a plurality of 10 sections, one of which is tiltably mounted in the recess and the other of which is horizontally movable toward and from said recess, means connecting said bed-frame sections whereby they automatically coöperate to 15 form a bed-frame of full length when in a horizontal position, and a counterbalancing means for assisting in the folding operation of one of the sections of the bed-frame.

7. A wall bed comprising the combination 20 with a wall having a recess or closet, of a tilttable section of bed-frame mounted in the closet, and a horizontally movable section connected to the tilttable section, said closet being substantially open on one side for the 25 outward movement of the tilttable frame section, and movable means for covering the open front when the bed-frame is concealed in the recess.

8. A wall bed comprising the combination 30 with a wall having a recess or closet, of a tilttable bed-frame mounted in the closet, said closet being substantially open on one side for the outward movement of the tilttable frame section, and movable sectional 35 means for covering the open front when the bed-frame is concealed in the recess.

9. A wall bed comprising the combination 40 with a wall having a recess or closet, of a tilttable bed-frame mounted in the closet, said closet being substantially open on one side for the outward movement of the tilttable frame, movable means for covering the open front when the bed-frame is concealed in the recess, said means comprising a horizontally movable cabinet structure, and an 45 automatically rising closure.

10. A wall bed comprising the combination 50 with a wall having a recess or closet, of a tilttable bed-frame mounted in the closet, said closet being substantially open on one side for the outward movement of the tilttable frame, movable means for covering the open front when the bed-frame is concealed in the recess, said means comprising a horizontally movable cabinet structure, an automatically raising closure, and means for interlocking the vertically movable closure 55 and the horizontally movable closure when the two are in juxtaposition to cover the opening of the recess.

11. A wall bed comprising the combination 60 with a wall having a recess or closet, of a tilttable bed-frame mounted in the closet, said closet being substantially open on one side for the outward movement of the tilt-

able frame, movable sectional means for covering the open front when the bed-frame is concealed in the recess, and means for locking the movable sections in juxtaposition to cover said opening.

12. A foldable bed structure comprising 70 fixed journal brackets, a shaft mounted in the brackets, a tilttable bed-frame mounted upon said shaft, means reacting upon the frame to tilt the latter to a vertical position, a horizontally movable section of the bed-frame, and a link structure connecting the horizontally movable section and the tilttable section whereby the latter section may be drawn down to a horizontal position to a line with the horizontally movable section.

13. A foldable bed structure comprising 75 fixed journal brackets, a shaft mounted in the brackets, a tilttable bed-frame mounted upon said shaft, counterbalancing springs 80 reacting upon the frame to tilt the latter to a vertical position, a horizontally movable section of the bed-frame, and a link structure connecting the horizontally movable section and the tilttable section whereby the latter section may be drawn down to a horizontal position to a line with the horizontally movable section.

14. A disappearing bed structure comprising 85 a bed-frame of a plurality of sections, each carrying a part of a mattress, a closet structure of a height substantially equal to one of said bed-frame sections, a journal in said closet for supporting said bed-frame section, and a horizontally movable carrier 90 in which the other section of the bed-frame is mounted, said sections coöperating to form, when horizontally aligned, a full length bed structure.

15. A disappearing bed structure comprising 95 a bed-frame, of a plurality of sections, each carrying a part of a mattress, a closet structure of a height substantially equal to one of said bed-frame sections, a journal in said closet for supporting said bed-frame section, and a horizontally movable carrier 100 in which the other section of the bed-frame is mounted, said sections coöperating to form, when horizontally aligned, a full length bed structure, the bed-frame section in the 105 carrier being slidably mounted therein and projecting from the rear side thereof when the structure is extended horizontally.

16. A wall bed comprising in combination 110 with a wall having a recess, of a bed-frame formed of separate coördinate sections, one of which is movable horizontally and the other of which is tiltably mounted in said recess, the recess being of a height approximately equal to the length of the tilttable 115 section.

17. A disappearing bed structure comprising 120 a bed-frame of coöperative sections, one of which is tiltably supported in a recess, the height of which is substantially equal to 125

the length of the tiltable section, and a carrier of a horizontal width and length substantially equal to and supporting the other section, said carrier and the recess coöperating to entirely conceal the bed-frame sections when moved into juxtaposition.

5 In testimony whereof we have hereunto

set our hands in the presence of two subscribing witnesses.
